UNITED STATES PATENT OFFICE.

GEORGE C. JORDAN, OF EAU CLAIRE, WISCONSIN.

RIDGE-ROLL FINIAL.

Application filed August 19, 1924. Serial No. 733,023.

To all whom it may concern:

Be it known that GEORGE C. JORDAN, a citizen of the United States of America, residing at Eau Claire, in the county of Eau Claire and State of Wisconsin, has invented new and useful Improvements in Ridge-Roll Finials, of which the following is a specification.

Heretofore ridge roll finials have been constructed in one piece and substantially rigid throughout, that is, in so far as that portion of the finial which engages with the ridge roll is concerned. Such construction of ridge roll finial prohibits nesting of finials which obviously prevents transportation of such articles in large quantities.

The present invention has for its purpose to provide, in a ridge roll finial, a construction thereof which will permit such devices to be packed and transported in large quantities, thereby permitting each package or container of ridge roll finials to contain practically over twice as many articles than may be transported in packages or containers of larger size where the articles are not capable of being nested.

Another purpose is to provide a ridge roll finial which may be constructed in one piece by means of a stamping process or by means of a drop forge method, the parts of the finial being so constructed as to permit large numbers to be nested for transportation.

Furthermore, in constructing the ridge roll finial in one piece, it is possible to bend the opposing parts or sections of the finial toward each other in order to position the parts of the base of the finial in order to engage with the base of the ridge roll and conform thereto.

Still another purpose is the provision of an improved finial wherein the upper opposed parts of the ridge roll of the finial are free and unattached to the two sections of the ball or globular member at the end of the finial. In fact, the opposed upper parts of the ridge roll of the finial overlap, rendering it possible to force together or pull apart the girth of the ridge roll of the finial in order that the finial may fit ridge rolls of different sizes.

A further purpose is the construction of a finial wherein the opposed parts of the ball or globular member are connected integrally by a portion of the sheet metal of which the finial is constructed so that, when the user or consumer desires to use such a

device, the opposed parts of the finial are bent toward each other until the marginal portions of the semi-spherical sections of the ball or globular member partly telescope in order to hold the opposed sections of the finial in register in order to insure rigidity and to properly engage the ridge roll. After the two sections of the ball or globular member so engage and the base of the finial is shaped, the various parts may be soldered, brazed or otherwise securely connected to hold the finial on the ridge roll.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in perspective of a portion of a ridge roll, showing the improved finial applied thereto in accordance with the invention.

Figure 2 is a longitudinal sectional view on line 2—2 of Figure 1, more clearly showing the construction of the finial and the overlapping parts of the ridge roll portion thereof.

Figure 3 is a transverse sectional view on line 3—3 of Figure 2.

Figure 4 is a sectional view on line 4—4 of Figure 1.

Figure 5 is a view in perspective of several finials opened up and nested together.

Figure 6 is a perspective view with the two parts of the ridge roll finial partly separated and showing where the upper portions of the ridge roll part of the finial are free and unattached relative to the semi-spherical sections of the ball or globular member.

Referring to the drawings, 1 designates the ridge roll and 2 denotes the ridge roll finial which is constructed from a single piece of sheet metal and comprises the opposed parts 3 which are integrally united by means of a piece of metal, as at 4. In fact, the metal 4 integrally connects the two semi-spherical sections of the ball or globular member 5 of the finial. The marginal portions of these two semi-spherical sections

telescope, as at 6, to hold the two sections rigid, especially until the two sections are soldered or otherwise connected.

Projecting from and integrally connected to the semi-spherical sections of the ball or globular member are the finial ridge roll portions 7 which are arcuate in cross section and their lower portions merge into the bases 8. The bases 8 engage with the base 10 of the ridge roll proper. The bases 8 have at their lower portions bent parts 9 with intermediate shoulders 10 which also conform to the base of the ridge roll proper. The bases 8 diverge downwardly and the 15 ends of said bases nearest the semi-spherical sections of the ball or globular member have flanges 11 which overlie the end of the ridge roll and are soldered or otherwise secured thereto in order to insure holding the finial 20 in position.

The ends of the upper parts of the ridge roll portions 7 of the finial, that is, adjacent the semi-spherical sections of the ball or globular member, are free and unattached 25 for a substantial distance which not only permits the two semi-spherical sections to partly telescope sufficiently to construct the ball or globular member but also render it possible to contract or pull apart or expand 30 the girth of the ridge roll of the finial, so that it may fit ridge rolls of different sizes. The upper parts of the ridge roll portions 7 overlap in order to permit the ridge roll of the finial to be expanded or contracted 35 so that it may accommodate itself to ridge rolls of different sizes. After the finial is placed in position, the overlapped parts of the ridge roll portions 7 may be soldered or otherwise secured together. While it 40 may be advisable in some instances and in most instances to solder or otherwise secure the parts of the finial together when in position, it is deemed sufficient to rely on the ridge roll to hold the parts of the finial in 45 place after it has been applied to the ridge roll.

The invention having been set forth, what is claimed is:

1. As an article of manufacture, a ridge 50 roll finial comprising opposed sections, each consisting of a semi-spherical part, a ridge roll portion and a base portion, the semi-

spherical sections being integrally connected, whereby the sections may be bent toward each other and caused to partly telescope 55 to construct a globular member or ball, said ridge roll portions having upper overlapping parts, whereby the finial may adapt itself to ridge rolls of different sizes.

2. As an article of manufacture, a ridge 60 roll finial comprising opposed semi-ridge roll portions with semi-globular sections at their corresponding ends, the upper parts of the semi-ridge roll portions adjacent the semi-globular sections being free and unat- 65 tached, whereby the semi-ridge roll portions may be contracted or expanded to accommodate ridge rolls of different sizes.

3. As an article of manufacture, a ridge 70 roll finial comprising opposed semi-ridge roll portions with semi-globular sections at their corresponding ends, the upper parts of the semi-ridge roll portions adjacent the semi-globular sections being free and unat- 75 tached, whereby the semi-ridge roll portions may be contracted or expanded to accommodate ridge rolls of different sizes, the semi-ridge roll portions having base parts 80 which engage with the base of the roof ridge roll, and means connecting the semi-globular sections, whereby the finial may be constructed in an open condition to permit several of them to be nested.

4. A nestable ridge roll finial constructed 85 from a single blank of sheet metal, comprising opposed semi-globular sections provided with ridge roll portions having base parts, and pliable means connecting the semi-globular sections, whereby the sections of the finial may be positioned together to fit the 90 ridge roll.

5. A nestable ridge roll finial constructed 95 from a single blank of sheet metal, comprising opposed semi-globular sections provided with ridge roll portions having base parts, and pliable means connecting the semi-globular sections, whereby the sections of the finial may be positioned together to fit the ridge roll, said ridge roll portions of the finial being expansible and contractible 100 to fit ridge rolls of different sizes.

In testimony whereof he affixes his signature.

GEORGE C. JORDAN.
